PRINTING DEVICE

Irving Gurwick, Mount Vernon, Ohio, assignor to
 Shellmar Products Company, Mount Vernon,
 Ohio, a corporation of Delaware

Application August 3, 1939, Serial No. 288,185

4 Claims. (Cl. 101—157)

The present invention relates to an improved color unit of the type employed in intaglio machines, and has particular reference to an improved ink applicator designed for use with intaglio printing units having a relatively high printing speed.

Intaglio printing units generally consist of a color bath in which rotates a conventional etched printing cylinder, the excess ink taken up by the printing cylinder being removed by a doctor blade before contact of the printing cylinder with a web to be decorated. Where the printing operation is to be done upon surfaces such as those afforded by transparent cellulose sheeting, difficulty often is encountered in properly supplying the etched portion of the printing cylinder with an adequate supply of ink, particularly at high speed.

A principal object of the present invention is the provision of an improved ink applicator for use with intaglio printing machines, in which an adequate supply of ink to the etched printing cylinder is insured at all speeds, even at relatively high speeds.

Another object is to provide an intaglio ink applicator in which ink is overflowed through a gap formed between the cylinder and a longitudinally extending ledge or wall of an overflow trough positioned so that the overhanging portion of the cylinder with respect to the trough is above the overflow ledge, the trough preferably being sufficiently narrow that less than one quadrant of the cylinder will be in contact with the ink in said trough.

Still another object of the invention is to provide an ink applicator for uniformly overflowing ink against the downwardly turning side of an etched printing cylinder regardless of the speed at which the cylinder is turning.

These and other objects will be evident upon a consideration of the following specification, and by reference to the accompanying drawings, in which—

Fig. 1 is a side view of a device constructed in accordance with my invention;

Fig. 2 is a sectional view taken along line 2—2 of Fig. 1; and

Fig. 3 is a fragmentary detailed sectional view taken along line 3—3 of Fig. 2.

The conventional form of ink applicator for intaglio printing presses consists of a tank-like color bath in which rotates an etched cylinder. As the etched cylinder passes through the ink contained in the color bath the ink adheres to the cylinder and prior to the printing operation the excess ink subsequently is removed by a doc-

tor mechanism. A great deal of difficulty has been encountered in uniformly applying ink to the cylinder when the press operates at relatively high speed. Various types of special ink applicators including manifold and pressure devices have been devised, but due to the delicacy of adjustment necessary and to the different operating conditions of the press, including such factors as printing cylinders of varying sizes, these special types of ink applicators have not met with success.

The construction of the present invention is shown as including an open, longitudinally extending ink or color tank or bath 10 which may be of conventional shape and construction. Within this color bath rotates an etched printing cylinder 11. As will be seen in Fig. 2, an impression roll 12 is mounted on the side of the printing cylinder so that the printing line is within the first quadrant of the printing cylinder. The course of the web to be printed is also indicated in this figure, the web being shown at 13. This web passes downwardly from the feed roll, or from the preceding color unit, through the color unit shown and then passes upwardly to the next color unit after the ink has dried.

The color bath 10 has mounted at each of its ends the overflow pipes 14, these pipes being situated beyond the ends of the cylinder 11. The tops of the pipes are provided with flanged sections 15 through which pass the adjustment screws 16, the latter having their ends resting upon the bottom of the tank 10.

The downwardly extending overflow pipes 14 pass through sleeve sections 17 which depend from the bottom of the color unit 10. The sleeves 17 and overflow member 14 deliver excess ink from the tank 10 to a reservoir to be described hereinafter. By turning the screws 16 it will be seen that it is possible to make an accurate adjustment of the ink level within the tank 10. As shown in Fig. 2, the bottom of the sleeves 17 have attached to them the flexible hoses 18, by which the excess ink is transferred back to the ink reservoir. The tank 10 may be carried in any suitable framework such as the members 19 shown in the drawings.

The ink normally employed in intaglio printing machines is of the quick-drying type in which the body of the ink is carried in a highly volatile solvent such as benzol, toluol, and the like. The inks most suitable for printing transparent cellulose sheeting are lacquer inks in which the body of the ink is composed of a cellulose derivative such as cellulose nitrate and a resin. Suitable

plasticizers may be employed to impart the desired flexibility to the ink. The ink may carry a soluble or insoluble pigment of any desired color.

Since an intaglio cylinder contacts the entire area of the web to be printed the previously deposited color is dried before the web reaches the next adjacent color for applications of fresh ink of the same or a different color. In high speed presses this has led to an increase in the volatility of the solvents employed in the process. It has been suggested to enclose the ink fountain in order to prevent loss of solvent by evaporation and a consequent increase in the density of the color. This leads to complicated construction which I have found can be avoided by suspending beneath the color bath a cooling chamber indicated generally at 20, this cooling chamber being supplied with chunks of ice indicated at 21 or other desirable cooling medium. The compartment 20 is formed by an inner metallic tank portion 22 and an outer metallic tank portion 23 suspended beneath the bottom of the color bath 10 by the releasable interlocking members 24 and 25 secured respectively to the tank 23 and the bottom of the tank 10. This construction permits withdrawal of the cooling tank for addition of ice. Any suitable securing means may be used to fold the opposite side of the cooling tank in position. Insulating material 26 is supplied between the sections 20 and 23.

The bottom of the color bath 10 is provided with a longitudinally extending plate 27 on the side of the tank adjacent the downwardly turning side of the cylinder 11, this plate being suitably brazed or otherwise attached to the color bath 10. At spaced intervals along its length the plates 27 in the bottom of the tank are supplied with openings through which extend the ink-supplying couplings 28. The couplings 28 have branch lines 29 communicating with a common supply line 30, which may be a flexible hose, leading to an ink reservoir 31 through a pump 32.

In color units of the type described hereinbefore the rapidly rotating cylinder tends to form a hollow spot between the cylinder and ink so as to prevent the cylinder from picking up an adequate supply of ink. Inferior printing is the direct result of this inadequacy. I have found that the fault may be remedied by supplementing or substituting for the conventional color bath a small overflow trough positioned in such a manner as to provide an underlying overflow gap with the cylinder, as will be described.

An upwardly extending baffle plate 33 is mounted on the floor of the tank 10 along the outside of the openings through which connections 28 extend. It is preferred that the upper portion of the baffle plate 33 be turned over, as shown in Fig. 2. The turned-over portion of the baffle plate 33 is spaced substantially from the printing cylinder and the upper portion of the baffle extends upwardly somewhat above the normal ink level in the tank 10. This turned-over portion acts as a means for more uniformly distributing in the overflow trough the ink which is pumped into the trough through the spaced connections 28.

On the opposite side of the ink supply sections 28 from the baffle 33 is mounted a second baffle 34 having at its upper portion a plate 35 constituting an overflow member which extends on an angle downwardly toward the printing cylinder 11. It is of importance to note that the end of the baffle or overflow plate 35 is spaced from the printing cylinder 11 so as to insure an overflow-

ing effect of ink spilling over the baffle against the side of the printing cylinder.

The printing cylinder itself forms a dam or wall which provides a gap between the cylinder 5 and the overflow trough below the level of ink in the latter, and ink in the trough contacts the printing cylinder above the overflow baffle. The frictional engagement of the cylinder with the ink increases the overflow between the baffle and cylinder as the latter rotates more rapidly, thereby insuring an adequate and sufficiently uniform ink deposition in the cylinder.

In Fig. 2 there is shown a shield 36 which extends between the conventional doctor mechanism 37 and the printing line. The doctor mechanism 37 removes excess ink from the printing cylinder and the volatility of the ink is such that under certain conditions substantial amounts of the solvent will evaporate from the etched portions of the cylinder between the doctor blade and the printing line. The shield 36 fits closely adjacent but spaced from the printing cylinder so as to provide a solvent atmosphere which will inhibit loss of solvents by the ink prior to application of the ink to the web to be decorated.

In the operation of the device an initial step consists in starting the pump 32 and pumping a relatively large volume of ink into the trough between the baffles 33 and 34. If the machine is 15 operating slowly the amount of ink will be more than can flow over baffle 35 adjacent the printing cylinder and the excess ink will flow over the baffle 33 to be returned through the overflow line to the ink reservoir. This provides a constant 20 level for the ink in the applicator trough as well as in the color bath 10 and an unlimited supply 25 which needs no adjustment or care. The baffle 35 affords an overflow of ink directly against the side of the printed cylinder on its downward travel. By adjusting the distance between the end of baffle 35 and the printing cylinder it is 30 possible to get any desired flow of ink from the applicator trough into the color bath 10. Thus, where a large flow is not desired it is sufficient to 35 provide a clearance between the baffle 35 and the printing cylinder of the order two one-thousandths of an inch. In some cases a larger opening will be desirable and this opening between the baffle 35 in the printing cylinder may be as much as one-eighth of an inch, or more.

It will be seen that the liquid level in the applicator trough between the baffles 33 and 34 is 40 higher than the liquid within the tank 10. This insures a uniform overflow of ink between the printing cylinder 11 and the baffle 35 and uniform 45 application of ink to the entire length of the cylinder regardless of the speed of the cylinder's rotation. As the rotation of the cylinder increases in speed, less of the ink will overflow the baffle 33 and more of it will be taken up by the printing cylinder. The applicator trough is open 50 to the atmosphere so that pressure does not develop therein.

The overflow characteristics provided by a 55 mechanism of this type have been found highly desirable in intaglio printing presses of the type employed in printing transparent cellulose sheeting at high speeds. For example, at speeds of 600 feet per minute an ordinary intaglio ink 60 trough is inadequate to provide uniform color distribution, possibly due to the centrifugal effect of the printing cylinder as it passes through the rotating bath of ink. The ink is thrown away from the cylinder as to prevent adequate adhesion. The overflow type of applicator described herein 65

overcomes these difficulties and does so in a satisfactory manner inasmuch as the device does not have to be adjusted and no particular regulation of the amount of ink supplied to the applicator trough is required. There is not incurred the danger of inadequate ink application by reason of changes of pressure or other factors.

It will be noted that the printing cylinder still rotates in a bath of ink in the color bath 10, but the ink within the bath 10 does not affect the application to the printing cylinder. It functions as an overflow reservoir for the applicator trough. Location of the applicator trough and the overflow baffle 35 on the downwardly turning side of the printing cylinder results in the latter assisting in the overflow function and the application of the ink. Thus, at higher speeds the printing cylinder may have an increased efficiency of application of ink. In many cases it will be found desirable to entirely eliminate the tank 10 and to recirculate the overflowing ink directly to and from a separate reservoir. Also, the position of the overflow trough may be changed from that shown in the drawings. In other positions the lowest portion of the cylinder in contact with the body of ink in or above the trough will still be above the overflow ledge of the trough, and the trough will be sufficiently small as to provide an ink supply contacting less than one quadrant of the printing cylinder. The overflow ledge of trough is on its lower side, as will be noted in the drawings.

It will be recognized that many changes may be made in the invention as described herein 35 for purposes of explanation, and such changes are intended to be included in the appended claims.

I claim:

1. In a device of the type described, a relatively narrow overflow trough having a substantially horizontal overflow ledge, means for sup-

plying ink to said trough, means for distributing the ink in the trough, and a rotatable cylinder overlying the trough and forming an overflow gap with said ledge, the lowest portion of said cylinder overlying said trough being above said ledge.

2. An intaglio printing unit, comprising a color bath, an etched printing cylinder rotating in said color bath, an overflow trough having a relatively high wall and a relatively low overflow wall forming an overflow gap with said printing cylinder on the underside thereof, means for receiving ink after it has overflowed from said trough, means for returning the ink to a reservoir, and means for circulating ink between said reservoir and said trough, that portion of the cylinder spanning the walls of said trough being above the overflow portion of said low wall, and said trough being sufficiently small to provide ink contact with less than one quadrant of the area of said cylinder.

3. An intaglio printing unit, comprising a color bath, means for controlling the level of liquid in said color bath, a printing cylinder rotating in said color bath, an overflow trough in said color bath on the downwardly turning side of said cylinder, said trough having an overflow plate below the liquid level in said color bath and extending adjacent but spaced from said cylinder and a second plate extending above the liquid level in said color bath, and means for supplying a higher head of ink in said trough than in said tank.

4. An intaglio printing unit, comprising a color bath provided with liquid level maintaining means, a printing cylinder rotatably mounted in said color bath with its lower side below said means, and an overflow trough adjacent said cylinder below its axis and on the downwardly turning side thereof, said trough having a downwardly inclined overflow ledge below said means.

IRVING GURWICK.
